Primary Examiner — Jennifer E. Novosad(74) *Attorney, Agent, or Firm* — Christine Flanagan**ABSTRACT**

A greeting card display having a vertical portion and a horizontal portion perpendicular to the vertical portion, a hook which is attached to the vertical portion of the display, and an insert panel which has a greeting card attached thereto and gets inserted onto the display. The display is operative to be inserted onto (over card retainer of) a greeting card display and to highlight specific cards, such as, for example, pop-up greeting cards.

GREETING CARD DISPLAYER

RELATED APPLICATIONS

This application is a non-provisional of and claims priority to U.S. Provisional Patent Application No. 62/966,692, which was filed on Jan. 28, 2020, a copy of which is incorporated herein by reference in its entirety.

FIELD OF THE INVENTION

This invention is in the field of retail fixtures for displaying social expression products, such as greeting cards.

SUMMARY OF THE INVENTION

In one embodiment, the present disclosure and related inventions describe a greeting card display having a vertical portion, a horizontal portion contiguous with and perpendicular to the vertical portion, each of the vertical and horizontal portions having a channel at each distal end thereof, a hook which is contiguous with and extends outward from an outer surface of the vertical portion of the display and an insert panel which is inserted between the channels at the distal ends of the vertical and horizontal portion, the insert panel operative to have a greeting card secured thereto.

In another embodiment, the greeting card display includes an L-shaped body with a vertical portion and a horizontal portion perpendicular to the vertical portion, the vertical and horizontal portions creating a 90-degree angle therebetween, a hook attached to an outer surface of the vertical portion of the L-shaped body, a first channel located at one end of the vertical portion of the L-shaped body and a second channel located at one end of the horizontal portion of the L-shaped body and an L-shaped insert panel which is inserted over an inner surface of the vertical and horizontal portions of the L-shaped body and which is held in place by the first and second channels.

In still another embodiment, a greeting card display contains a body having a vertical portion and a horizontal portion perpendicular to the vertical portion, creating a substantially L-shaped body, a first channel at a distal end of the vertical portion of the body, a second channel at a distal end of the horizontal portion of the body, an insert panel having a vertical portion and a horizontal portion perpendicular to the vertical portion, creating a substantially L-shaped insert panel, and an upside-down u-shaped channel located on a rear surface of the vertical portion of the body.

DESCRIPTION OF THE DRAWINGS

FIG. 1 is a front right side perspective view of the GREETING CARD DISPLAYER of the present invention attached to a greeting card display fixture and with a greeting card inserted therein.

FIG. 2 is a right side view thereof.

FIG. 3 is a perspective view thereof.

FIG. 4 is a front right side perspective view thereof with greeting card removed therefrom.

FIG. 5 is a rear right side perspective view thereof with greeting card removed therefrom.

FIG. 6 is a front elevation view thereof.

FIG. 7 is a right side elevation view thereof.

FIG. 8 is a front perspective view of the GREETING CARD DISPLAYER of the present invention attached to a greeting card display fixture with a greeting card inserted therein.

FIGS. 9-11 are front perspective views of the GREETING CARD DISPLAYER with various pop-up cards inserted therein.

DETAILED DESCRIPTION OF PREFERRED AND ALTERNATE EMBODIMENTS

The greeting card display (hereinafter referred to as "the display") 10 of the present disclosure and related inventions displays and highlights cards 12 and can be attached to a card retainer on a variety of different greeting card fixtures 14. The display 10 can accommodate the presentation of a variety of different greeting cards 12 by allowing for different insert panels 16.

The display 10 has an L-shape with a first or vertical portion 10A and a second or horizontal portion 10B contiguous with and perpendicular to the first or vertical portion 10A. Each of the first and second portions 10A, 10B of the display have a first end and a second end. The first and second portions connect at the first end, forming a 90-degree angle. There is a small u-shaped channel at each distal (or second) end 10C, 10D of the first and second portions 10A, 10B. These channels 10C, 10D are used to hold an insert panel 16 in place on the display 10. In one embodiment, the first or vertical portion 10A of the display 10 is approximately 6-inches long and the second or horizontal portion 10B of the display 10 is approximately 4.5-inches long. The second panel 10B extends past the connection point with the first panel 10A approximately 0.25-inches, as can be seen in FIG. 7. There is also a small notch 10E extending outward and perpendicularly from the first panel 10A at approximately 1.5-inches from the first end of the first panel 10A (connection point with the second panel). In one embodiment, the width of the space between the u-shaped channels 10C, 10D located at each second end of the first and second panels 10A, 10B of the display 10 is approximately 0.063-inches. A hook H is attached to an outer surface of the first or vertical panel 10A in an upper portion thereof, as shown in FIGS. 2, 5 and 7. The hook H, in one embodiment, is contiguous with the first panel 10A of the display 10. In other embodiments, the hook H may be a separate element which is attached to the display 10. The hook H is located approximately 4-inches from the first end of the first panel 10A. The hook H extends outward from and perpendicular to the first panel 10A then continues downward (parallel to the first panel 10A) and then curves to the right, then to the left, creating a slightly curved section. The channel 18 created between the downward section of the hook H and the first panel 10A is approximately 0.5-inches. The space between the curved section of the hook H and the first panel 10A is approximately 0.25-inches. The hook H is designed to be flexible enough to cradle over and snap onto a card retainer (also referred to as a front card sham or front card wall) 20, which typically vary between 0.188-inches and 0.375-inches. The flexibility of the hook H allows the display 10 to be used (attached to) a variety of card tiers 20 and fixture lines. In one embodiment, the display 10 and hook H are made of extruded plastic, although other somewhat flexible materials can be used. While various dimensions have been given with respect to the display 10, these are given only for descriptive purposes in a particular embodiment. Various other dimensions may be used. These dimensions are not intended to limit the scope of the present invention in any way.

The display 10 of the present disclosure and related inventions is particularly useful for displaying pop-up or three-dimensional cards at retail. Typically, these cards must

be removed from the card tier and opened to view the inside of the card and the pop-up structure. The display 10 facilitates the display of these hard-to-display greeting cards at retail. To display a greeting card 12 upon the display 10, the greeting card 12 must first be attached to an insert panel 16. The insert panels 16 are sized to be able to fit within the channels 10C, 10D at the second ends of the first and second panels 10A, 10B of the display 10 and also thick enough to create a friction fit within the channel 10C, 10D to avoid the insert panel 16 from inadvertently being removed from the channels 10C, 10D. The insert panels 16 may be of different widths, depending on the type of greeting card 12 displayed, how the greeting card 12 is staged with regard to presentation, and how the greeting card 12 functions. For example, a pop-up greeting card 12 may be fully opened and attached to the insert panel 16 (along the second or horizontal display panel 10B), as shown in FIGS. 1, 2 and 11. In another example, a 90-degree pop-up card 12 may be opened at a 90-degree angle such that the one greeting card panel is attached to the insert panel (along the first or vertical portion of the display) 10A and the other greeting card panel is attached to the insert panel (along the second or horizontal portion of the display) 10B, as shown in FIG. 9. The insert panels 16 may also be used to display verbiage, advertising, or graphical elements.

The foregoing embodiments of the present invention have been presented for the purposes of illustration and description. These descriptions and embodiments are not intended to be exhaustive or to limit the invention to the precise form disclosed, and obviously many modifications and variations are possible in light of the above disclosure. The embodiments were chosen and described in order to best explain the principle of the invention and its practical applications to thereby enable others skilled in the art to best utilize the invention in its various embodiments and with various modifications as are suited to the particular use contemplated. It is intended that the invention be defined by the following claims.

The invention claimed is:

1. A greeting card display comprising:

an L-shaped body having a vertical portion, and a horizontal portion contiguous with and forming a 90-degree angle with respect to the vertical portion, each of the vertical and horizontal portions having a channel at each distal end, opposite the 90-degree angle, the channel running the entire length of the vertical and horizontal portions of the L-shaped body;
 a hook which is contiguous with and extends outward from an outer surface of the vertical portion of the L-shaped body; and
 an L-shaped insert panel having a vertical panel and a horizontal panel contiguous with and perpendicular to the vertical panel, wherein a portion of the vertical panel is inserted into the channel at the distal end of the vertical portion of L-shaped body and a portion of the horizontal panel is inserted into the channel at the distal end of the horizontal portion of the L-shaped body; wherein the L-shaped insert panel is operative to have a greeting card secured thereto.

2. The greeting card display of claim 1, wherein the hook is operative to clip onto the front panel of a greeting card tier.

3. The greeting card display of claim 1, wherein the insert panel is interchangeable.

4. The greeting card display of claim 1, wherein the insert panel can be used for advertising or graphical elements.

5. A greeting card display comprising:

an L-shaped body with a vertical portion and a horizontal portion perpendicular to the vertical portion, the vertical and horizontal portions creating a 90-degree angle therebetween;
 a hook attached to an outer surface of the vertical portion of the L-shaped body;
 a first channel located at one end of and spanning the entire length of the vertical portion of the L-shaped body and a second channel located at one end of and spanning the entire length of the horizontal portion of the L-shaped body;
 an L-shaped insert panel which is inserted over an inner surface of the vertical and horizontal portions of the L-shaped body and which is held in place by the first and second channels;
 wherein the horizontal portion of the L-shaped body is longer than the vertical portion.

6. The greeting card display of claim 5, wherein the hook is operative to be placed over a front sham of a greeting card row.

7. The greeting card display of claim 5, wherein the L-shaped insert panel is interchangeable.

8. The greeting card display of claim 5 further comprising a notch attached to the outer surface of the vertical portion of the L-shaped body.

9. The greeting card display of claim 5, wherein the hook is contiguous with the vertical portion of the L-shaped body.

10. A greeting card display comprising:

a body having a vertical portion and a horizontal portion perpendicular to the vertical portion, creating a substantially L-shaped body;
 a first channel located on and running the entire length of the horizontal portion of the body opposite an intersection between the horizontal and vertical portion of the body;
 a second channel located on and running the entire length of the vertical portion of the body opposite the intersection between the vertical and horizontal portion of the body;
 an insert panel having a vertical portion and a horizontal portion perpendicular to the vertical portion, creating a substantially L-shaped insert panel;
 wherein the horizontal portion of the insert panel is inserted into the first channel and the vertical portion of the insert panel is inserted into the second channel;
 an upside-down U-shaped channel located on a rear surface of the vertical portion of the body.

11. The greeting card display of claim 10, wherein the insert panel is operative to have a greeting card attached thereto.

12. The greeting card display of claim 10, further comprising an upside-down U-shaped channel located on a rear surface of the vertical portion of the body that is operative to be attached to a front panel of a greeting card tier.
